UNITED STATES PATENT OFFICE.

JAMES N. MARTIN AND ASHER SENOR BRAGAN, OF BIRMINGHAM, ALABAMA.

SMOKE AND HEAT GENERATOR.

1,275,959.

Specification of Letters Patent. Patented Aug. 13, 1918.

Application filed June 8, 1917. Serial No. 173,573.

To all whom it may concern:

Be it known that we, JAMES N. MARTIN, and ASHER SENOR BRAGAN, citizens of the United States, both residing at Birmingham, in the county of Jefferson and State of Alabama, have invented certain new and useful Improvements in Smoke and Heat Generators; and we do hereby declare the following to be a full, clear, and exact description of the invention, such as will enable others skilled in the art to which it appertains to make and use the same.

The present invention relates to improvements in smoke generators, and has for an object to provide an improved smoke generator in which the smoke chamber will be entirely independent and disconnected from the furnace or fire box, and constructed with a secondary smoke chamber for receiving the smoke after circulation in the smoke house and re-heating and returning the same.

With these and other objects in view the invention consists in the novel details of construction and combinations of parts more fully hereinafter disclosed and particularly pointed out in the claims.

In the accompanying drawings forming a part of this application, and in which similar reference symbols indicate corresponding parts in the several views:

Figure 1 is a rear perspective view of an improved smoke generator constructed in accordance with the present invention.

Fig. 2 is a front elevational view of the same.

Fig. 3 is a longitudinal central sectional view of the improved generator.

Fig. 4 is a transverse sectional view taken on the line 4—4 in Fig. 3;

Fig. 5 is a sectional view of a detail, and

Fig. 6 shows a vertical sectional view through a smoke house and our improved generator.

Referring now more particularly to the drawings, the improved device is built up of any suitable material to provide a furnace or fire box 1, in which are mounted fire bars 2 constituting a grate beneath which is an ash pit 3.

The fire box 1 and ash pit 3 are accessible through swinging or other doors 4 and 5, shown in the present instance to be mounted respectively on pintles 6 and 7 journaled in pairs of bearings 8 and 9 secured to the front wall 10 of the structure.

The rear wall 11 is perforated to receive a pipe 12 arranged to communicate with a chimney for carrying off the products of combustion and providing for a draft. 60

Above the fire box or furnace 1 is a floor or partition 13 separating the same from a smoke chamber 14. This smoke chamber is accessible preferably through two doors 15 and 16, which may be mounted to swing 65 on pintles 17 and 18, as above described for the doors 4 and 5.

The smoke chamber 14 is contained within longitudinal side walls 19 and 20, a rear end wall 21, and a roof 22, the same being 70 spaced from the side walls 23 and 24 of the structure, from the rear wall 11 and from the roof 25 thereof. The space so formed is arranged to constitute a secondary smoke chamber which is connected to 75 the smoke house through a pipe 26 for receiving and returning the smoke therefrom, as indicated in Fig. 3, by the arrows. This pipe 26 has a branch 27 communicating with the atmosphere, and at the junction of pipe 80 and branch is located a damper 28 for regulating the supply of air to control the density of the smoke.

A pipe 29 is fitted in the roof 22 of the smoke chamber 14, and such pipe 29 is 85 fitted centrally within and spaced from a collar or pipe 30 secured to the roof 25 of the generator structure, such collar 30 being in communication, as clearly shown in Figs. 3 and 4, with the secondary smoke chamber 90 31.

In the pipe 29 is a damper 32 operated by a handle 33 from the front 10, or other part of the generator, as desired. A strainer or spark arrester 34 is stretched across the pipe 29 and may be extended also across the 95 collar 30, and the same acts to prevent dust or sparks from entering the smoke room. The collar 30 and pipe 29 are connected by a pipe 41 with the lower part of a smoke house 42 appearing in Fig. 6, where the meats, etc., are to be treated, and the pipe 26 is connected to the roof thereof as indicated at 43 also in Fig. 6. If found desirable or necessary, a circulating fan 40 may be placed in the circuit. 100

In the use of the device the wood or other smoke generating material is introduced into the smoke chamber 14 through either or both doors 15 and 16 which are swung upwardly about their pintles to give access thereto. Subsequently these doors are closed, and fuel is introduced through the 110

- door 4 and distributed over the fire bars 2 in the fire box 1. The same being then ignited will heat the wood in the smoke chamber 14 and cause the wood to give off smoke 5 which will pass up through the pipes 29 and 41, as controlled by the damper 32, and to the smoke house 42 where the smoke will circulate about. The smoke in the smoke house 42 which has not been utilized will 10 pass to the pipe 26, under the influence of the circulating fan, and be conveyed therethrough back to the secondary smoke chamber 31 in a volume controlled by the damper 28, which, if the smoke is thin, may be moved 15 to open wide the pipe 26 and effectually close the branch 27, preventing access of air thereto. If the smoke is thicker and denser than desired, the damper 28 may be moved to open the branch 27 as required, thereby 20 permitting the current of smoke passing through the pipe 26 to draw in air from the atmosphere, which, becoming mixed therewith, will thin out the smoke. The smoke returning through the pipe 26 to the secondary 25 chamber 31 will circulate about the walls and roof of the chamber 14 and will again become heated, subsequently passing out through the collar 30 and returning to the smoke house where it is again utilized. 30 It is obvious that those skilled in the art may vary the details of construction and arrangements of parts without departing from the spirit of our invention, and therefore we do not wish to be limited to such features 35 except as may be required by the claims.

We claim:

1. The combination with a smoke house, of an improved smoke generator therefor including a fire-box, a primary smoke chamber above said fire-box, a secondary smoke chamber partly surrounding said first-named chamber, means for conveying smoke from both the primary and secondary chambers to said smoke house, and a flue for returning the smoke from the smoke house to said secondary chamber, substantially as described.
2. The combination with a smoke house, of an improved smoke generator therefor in-

cluding a fire-box, a primary smoke chamber located above and non-communicating with respect to said fire-box, a secondary smoke chamber, means for conveying smoke from said primary and secondary chambers to said smoke house, a flue for returning the smoke from the smoke house to said secondary chamber, and means for introducing air to said secondary chamber whereby to thin the smoke to the required density, substantially as described. 50

3. The combination with a smoke house, of an improved smoke generator therefor comprising a fire-box, a primary chamber heated by the fuel in the fire-box and in which the smoke is initially generated, a secondary smoke chamber in which the smoke is re-heated, means for connecting both said primary and secondary chambers with said smoke house, a flue for returning the smoke from the smoke house to said secondary chamber, a fan for promoting a circulation of the smoke through said flue, a branch in said flue in communication with the atmosphere, and a valve at the junction of said branch and flue for controlling the passage of smoke through the flue and of air through the branch, substantially as described. 60 65 70 75

4. The combination with a smoke house, of an improved smoke generator therefor comprising a fire-box, a primary smoke chamber located above said fire-box, a pipe rising from said primary smoke chamber, a secondary smoke chamber partly surrounding said primary chamber, a collar surrounding said pipe and providing an outlet for the smoke from said secondary chamber, means for conveying the smoke from said pipe and collar to said smoke house, a flue for returning the smoke from the smoke house to said secondary chamber, an air inlet in said flue, and means for controlling the passage of the smoke through and the air into said flue, substantially as described. 80 85 90

In testimony whereof, we affix our signatures.

JAMES N. MARTIN.
ASHER SENOR BRAGAN.
